DESIGN FOR A TIRE

John G. Rideout, Cleveland, Ohio, assignor to
The B. F. Goodrich Company, New York, N. Y.,
a corporation of New York

Application November 29, 1940, Serial No. 96,952

Term of patent 14 years

To all whom it may concern:

Be it known that I, John G. Rideout, a citizen of the United States, residing at Cleveland, in the county of Cuyahoga and State of Ohio, have invented a new, original, and ornamental Design for a Tire, of which the following is a specification, reference being had to the accompanying drawing, forming a part thereof, of which:

Fig. 1 is a side elevational view of a tire, the portion in dotted lines being partly broken away

for convenience in illustration, showing my new design.

Fig. 2 is a section taken along the line 2—2 of Fig. 1.

Fig. 3 is a fragmentary side elevational view of the tire on an enlarged scale.

I claim:

The ornamental design for a tire, as shown.

JOHN G. RIDEOUT.
